UNITED STATES PATENT OFFICE.

JAMES S. McQUINN, OF NEWCASTLE, INDIANA.

DESIGN FOR A GLASS PANEL.

41,286.

Specification for Design.

Patented Apr. 4, 1911.

Application filed February 25, 1910. Serial No. 546,038. Term of patent 7 years.

To all whom it may concern:

Be it known that I, JAMES S. McQUINN, a citizen of the United States, residing at Newcastle, in the county of Henry and State of Indiana, have invented a new, original, and ornamental Design for a Glass Panel, of which the following is a specification, reference being had to the accompanying drawing, forming a part hereof.

The figure is a plan view of a glass panel showing my new design.

I claim:

The ornamental design for a glass panel, as shown.

JAMES S. McQUINN. [L. s.]
